UNITED STATES PATENT OFFICE.

HEINRICH BROCK, OF KNAPSACK, NEAR COLOGNE, GERMANY.

WIRING SYSTEM FOR TRANSFORMERS FOR MULTIPHASE FURNACES.

Application filed March 15, 1927, Serial No. 175,585, and in Germany October 14, 1925.

Multiphase supply mains—such as are most useful for three-phase current—which serve for transmitting energy from transformers to electrically-heated smelting furnaces, can carry extraordinarily high currents, since the voltages employable for smelting furnaces are very limited. The lower the voltages are in relation to the strengths of current, the more constant is the fusing arc and also the running of the furnace, for example with combined arc and resistance furnaces. With a given group of alternating current transformers,—the latter may consist either of one three-phase transformer or three single-phase transformers—the smallest voltages are obtained upon the low tension side, which lies towards the smelting furnace, by means of the so-called delta-connection. The voltages between each two phases are in this case the same as the phase voltages, whilst the current strengths are 1.73 times the current strengths of the phases. The high tension sides of the transformers are, as heretofore provided connected up on the delta system of connection and the low tension sides of the transformers are also connected up on the same system; the low tension connections being made directly at the transformers in accordance with the connections of the phases on the high tension side, as hitherto customary. The three phases thus obtained are then taken to each electrode of the furnace. Detrimental to the power factor of the supply system are, not only the direct transformer connections, but also the single-phase lines to the electrodes; induced by the high currents the electromagnetic fields of the transformer connections, are only incompletely compensated, and the single-phase lines to the electrodes are not compensated at all.

The invention more particularly described hereafter overcomes the drawback of the uncompensated fields and so gives a better power factor for the network. The invention is illustrated diagrammatically in the

accompanying drawing wherein the figure illustrates the system of connection for a three phase current. 50

In the drawing, a_1 b_1 and c_1 are three single-phase transformers, d_1 e_1 and f_1 the three electrodes of the electrically-heated smelting furnace. The low tension sides of the three transformers are led to the electrodes in the manner shown. The commencements of the single phases are marked 1 and the ends of the same 2. The current passing in the conductor a_1 s_1 — f_1 and the conductor a_1 s_2 — d_1 has at every instant the same magnitude but reversed direction, so that the outwardly-radiated electromagnetic field becomes null with the technically obtainable juxtaposition of the two conductors. The same applies for the conductors of the other phases. The currents belonging to each electrode—each a commencement and an end of two phases—are not united at the transformer as formerly, and then led to the electrode in single phases, but are first combined at the corresponding electrode at a value of 1.73 times the current of the phases, which value is only applicable for the mesh-connection with three-phase current. 60 65 70 75

It will be readily understood that the invention may also be employed for a different number of phase currents as regards the wiring system relating thereto.

I claim:—

An alternating current distributing system designed for an electric furnace and wherein it is desired to reduce the self inductance due to the large currents used, which comprises a plurality of transformers, a plurality of electrodes, and wires from the secondaries of said transformers leading to the said electrodes, the lead and return wires of each secondary winding extending to said electrodes in a substantially adjacent and parallel relation, the wires being connected to the electrodes and to each other through the electrodes. 80 85 90

HEINRICH BROCK.
